(57) **CLAIM**

The ornamental design for a divider panel for an animal cage, as shown and described.

DESCRIPTION

FIG. 1 is a perspective view of a divider panel for an animal cage that illustrates the novel design;
FIG. 2 is a top view of the divider panel of FIG. 1;
FIG. 3 is a left side elevational view of the divider panel of FIG. 1;
FIG. 4 is a right side elevational view of the divider panel of FIG. 1;
FIG. 5 is a bottom view of the divider panel of FIG. 1;
FIG. 6 is a front view of the divider panel of FIG. 1; and,
FIG. 7 is a back view of the divider panel of FIG. 1.
